UNITED STATES PATENT OFFICE

MCLENNEN C. SLATE, OF ALBANY, OREGON, ASSIGNOR TO SLATE CONSTRUCTION COMPANY, OF ALBANY, OREGON

HYDRAULIC CONTROL APPARATUS FOR SCRAPERS

Application filed October 10, 1929, Serial No. 398,685. Renewed January 14, 1931.

The object of my invention is to provide a novel hydraulic control apparatus for controlling the operation of a scraper and particularly to positively and automatically control the digging angle of the scraper and for permitting of such control from a distance as from the seat of the tractor, by means of cords connected with levers arranged to operate valves or other mechanism of the hydraulic apparatus; and it is an object of my invention to provide a novel combination of elements and the novel means for arranging, mounting and adjusting the mechanism disclosed in the accompanying drawings and hereinafter described.

I attain these and other objects of my invention by the apparatus illustrated in the accompanying drawings, in which,—

Figure 1 is a side elevation of my invention with the piece 14 held in a forward position, thus causing a tilting of the body of the scraper and the placing of its entire weight upon its cutting blade;

Fig. 2 is a side elevation of the scraper in dumping position and the relative position of the control apparatus when it is in that position;

Fig. 3 is a side elevation of the scraper in normal position for hauling;

Fig. 4 is a top plan view of the hydraulic control apparatus; and

Fig. 5 is a side elevation of the hydraulic control apparatus with portions of the mechanism broken away and shown in vertical section.

Like numerals designate like parts in each of the several views.

Referring to the accompanying drawings I provide a suitable scraper body 1 having runners 2 and a bottom and cutting blade 3. I provide a tongue for the scraper with a releasable slide member 7 slidably mounted on the underside of the tongue and to which the ends 6 of a plurality of pulling rods 5 are loosely mounted, the rear ends 4 of said pulling rods 5 being loosely mounted in the scraper body as shown in Figs. 1, 2 and 3. The slide member 7 is operatively connected with the trip lever 10 and may be released so as to slide on the tongue 8 by operating that

lever, the lever having a cord 11 running from it to the seat of the tractor within reach of the operator. I provide an extension or link 9 on the end of tongue 8, as shown in Fig. 1.

Mounted on the tongue 8 is a bracket 12 on which the hydraulic control apparatus is mounted by means of the pivot connection 13 as shown in Figs. 1 and 3.

Affixed to the rear of the body of the scraper are spaced posts 14 which are connected by the pin or bolt 15 which extends through the slot 17 in the rear end of the tongue 8. The upper ends of the post 14 are provided with apertures in which the projections 16 of the movable piece 20 are mounted. The piece 20 has a bolt 20a extending vertically through it and through the slots 20b of members 18, this element functioning to keep the movable piece in its proper slidable relation in the slot 19 between the spaced plates 18.

Referring to Figs. 4 and 5 there is illustrated my hydraulic apparatus consisting of the cylinders 21 and 22 containing oil or other suitable liquid. In the cylinder 22 is mounted a piston 25 which is connected by a suitable connecting rod 26 with the spaced parallel plates 18, the connecting rod 26 being slidably mounted in a casing 27, as shown in Fig. 5. Opening out of the cylinder 22 is a conduit 28 at the rear end of the cylinder which conduit communicates with the pipe 29 which encircles the cylinder and which also is in communication with the forward end of cylinder 22 through the conduit 33. I provide a check valve 31 in pipe 29 and a pipe cross connection 32, as shown in Fig. 4; and a relief valve 23 which is equipped with a check valve 24 as shown in dotted lines in Fig. 4. I provide a relief port 34 connecting cylinder 22 with cylinder 21 as shown in Fig. 5, which permits the liquid to flow from cylinder 22 to cylinder 21 to compensate for the space occupied by connecting rod 26 when piston 25 is at the forward end of cylinder 22.

Valve 23 is controlled by a lever 24' which in turn is operated by a rope 25' which extends to a convenient position within reach of the operator on the tractor driver's seat.

In operation as the scraper is dumped, posts 14 automatically assume the position

relative to the tongue 8, as shown in Fig. 2. At the same time, this action causes oil that is on the forward side of the piston 25 to pass to the rear of said piston, the oil first passing through conduit 33 into pipe 29, past

5 check valve 31 and through conduit 28 to the rear of piston 25. Fig. 5 shows a piston in the position in which it stands when the scraper is in its normal hauling position.

10 When the scraper is in the position shown in Fig. 2, the piston 25 will be moved to the forward end of the cylinder 22. Now if the scraper body 1 is returned to a digging position, such as that shown in Fig. 1, the pis-

15 ton cannot return to the rear end of the cylinder because of entrapped oil in rear portion of the cylinder 22. A small portion of oil must pass through a relief port 34, communicating between cylinder 22 and reservoir 21,

20 as shown in Fig. 5, because when the piston is in the forward end of cylinder 22, connecting rod 26 occupies an appreciable amount of the volume inside the cylinder.

25 After the scraper has been filled with earth, by-pass valve 23 is operated by a pull on the rope 25' which actuates the lever 24', which in turn operates the valve 23. The piston will then move to the rear end of the cylinder and the oil that was previously entrapped behind the piston will pass through

30 the by-pass valve 23, through pipe 29 to the forward end of cylinder 22 and enough oil to compensate for the volume of the connecting rod 26 will pass in from the reservoir 21

35 through the relief port 34. This will allow the body 1 of the scraper to tilt backward into a hauling position, such as shown in Fig. 3. When the scraper is dumped the above de-

40 scribed action will again take place.

Referring to Fig. 4, as a means of securing adjustment of the apparatus to the desired digging angle, I provide in cylinder 22 a number of outlets 43, 44, 45 and 46 placed at various points on rear end of the cylinder and connected with outlets 47 or 48 on the forward end of the cylinder. Note that near the outlets 43, 44, 45 and 46 are placed cocks

45 49, 50, 51 and 52. Now if say cock 49 is opened and all others closed it is evident that the piston after being pushed to the forward end of the cylinder can return part way when the scraper is returned to the loading position.

Now, if cock 49 is closed and any one of the others opened the piston would travel back to the corresponding position, thus adjusting the digging position of the scraper accordingly.

The by-pass adjustment cocks 49, 50, 51 and 52 provide a control which will automatically return the scraper to any one of the several desired angles without attention of the tractor operator. Also the tractor driver can secure an infinite number of digging positions by use of cord 25'.

What I claim is:

1. In apparatus of the class described, the combination of a scraper, pulling rods pivotally connected with the forward end of the scraper, a tongue on the scraper, a slide member slidably mounted on the tongue and to which member the pulling rods are operatively connected, means operable at a distance for releasing the slide member, posts affixed to the rear of the scraper, and extending 70 above the top of the scraper, a bracket mounted on the tongue of the scraper, hydraulic apparatus pivotally connected to said bracket, said hydraulic apparatus including a connecting rod having spaced plates attached to it, a movable piece mounted between the plates and having a limited range of movement, said piece having projections pivotally engaging the upper ends of the posts affixed to the rear of the scraper, and means for controlling the operation of the hydraulic apparatus from a distance, whereby the digging angle may be controlled from a distance and whereby the machine will automatically be placed in such a position that the loading operation may be 80 commenced at once whenever the scraper is returned from a dumping position to a digging position without attention on the part of the tractor operator.

2. In apparatus of the class described, the combination of a scraper, pulling rods pivotally connected with the forward end of the scraper, a tongue on the scraper, a slide member slidably mounted on the tongue and to which member the pulling rods are operatively connected, means operable at a distance for releasing the slide member, posts affixed to the rear of the scraper, and extending above the top of the scraper, a bracket mounted on the tongue of the scraper, hydraulic apparatus pivotally connected to said bracket and having an operative connection with the upper ends of the posts to limit the angle to which the scraper can be returned from dumping position.

3. In hydraulic apparatus for tilting a scraper to a desired digging angle, the combination of a scraper body, posts affixed to the rear of the scraper, and extending above the top of the scraper, a tongue having a limited slideable connection with said posts at a point above the scraper but below the upper ends of the posts, hydraulic apparatus for limiting the angle to which the scraper can be returned from dumping position, means for operatively connecting the hydraulic apparatus with the upper ends of the posts, a piston to which said means are attached, a main cylinder in which the piston is slidably mounted, an auxiliary cylinder with which the main auxiliary cylinder has a fluid connection, conduits opening out of opposite ends of the main cylinder, an encircling pipe with which each of said conduits communi- 130

cate, check valves in said pipe, and means for manually operating one of the valves.

4. In hydraulic apparatus for controlling a scraper, the combination of a scraper body, 5 posts affixed to the rear of the scraper and extending above the top of the scraper, a tongue having a limited slideable connection with said posts at a point between the top of the scraper and the upper ends of the posts, 10 hydraulic apparatus for controlling the digging angle of the scraper body, a link member operatively connecting said hydraulic apparatus with the upper ends of the posts, said apparatus including a piston to which 15 said link member is attached, a main cylinder in which the piston is slidably mounted, an auxiliary cylinder, a fluid connection between the main cylinder and the auxiliary cylinder, conduits opening out of opposite ends of the 20 main cylinder, an encircling pipe with which each of said conduits communicates, check valves in said pipe, and valve mechanism for controlling the operation of the above described hydraulic apparatus, said mechanism being operable from a distance.

5. In combination with the apparatus defined in claim 3 a relief valve mounted in the pipe which encircles the cylinder.

6. In an apparatus of the class described, 30 the combination of a scraper body, posts affixed to the rear of the scraper body and extending substantially above the top of the scraper body, a draft device having a slideable and pivotal connection with the said 35 posts at a point spaced substantially from the top of the posts, a hydraulic control apparatus including a piston, connecting rod, and spaced plates attached to the connecting rod, a movable piece mounted between said 40 spaced plates and having a pivotal connection with the top of the aforesaid posts, valve mechanism connected with the hydraulic apparatus and operable from a distance.

7. In an apparatus of the class described, 45 the combination of a scraper body; posts affixed to the rear of the scraper body said posts extending substantially above the top of the scraper body; a draft device having a slideable and pivotal connection with the said 50 posts at a point spaced from the top portion thereof; a hydraulic control apparatus including a piston, connecting rod, and spaced plates attached to the connecting rod; a movable plate mounted between said spaced 55 plates and having a pivotal connection with the top of the aforesaid posts, valve mechanism connected with the hydraulic apparatus and operable from a distance for controlling the operation of the hydraulic apparatus to regulate the digging angle of the scraper, an operating lever mounted on the draft device and operable from a distance, a slide member releasable by said lever, pulling rods connected with said slide member and with the 60 bottom forward portion of the scraper.

8. In combination with the apparatus defined in claim 6, the combination of an operating lever mounted on the tongue of the scraper and operable from a distance, a slide member releasable by said lever, pulling rods 70 connected with said member and with the bottom forward portion of the scraper.

9. In an apparatus of the class described, the combination of a scraper body, posts affixed to the rear of the scraper and extending considerably above the top of the scraper, 75 a tongue connected with said posts and also with the forward portion of the body of the scraper for tilting the scraper, and a hydraulic apparatus operatively mounted on the tongue and operatively connected with the upper ends of the posts and means operable from a distance for controlling the hydraulic apparatus whereby to regulate and control the operative position of the scraper 80 and its digging angle.

10. In an apparatus of the class described, the combination of a scraper body, posts affixed to the rear of the scraper and extending considerably above the top of the scraper, 90 a tongue connected with said posts and also with the forward portion of the body of the scraper for tilting the scraper, and a hydraulic apparatus operatively mounted on the tongue and operatively connected with the upper ends of the posts, the hydraulic apparatus being arranged and adapted for automatically and positively controlling the return of the scraper body to a desired digging angle after being dumped, and means 95 operable from a distance for controlling the hydraulic apparatus whereby to regulate and control the operative position of the scraper 100 and its digging angle.

11. In an apparatus of the class described, the combination of a scraper body, a tongue, a hydraulic control unit mounted on the tongue, posts affixed to the scraper body and extending above same and to which the hydraulic apparatus is connected said hydraulic apparatus including means for automatically regulating and limiting the return movement from digging position of the body of the apparatus to its hauling position without the attention of the operator.

12. In apparatus of the class described, the combination of a tongue, a hydraulic control unit mounted on the tongue, posts affixed to the scraper body and extending above same and to which the hydraulic apparatus is connected said hydraulic apparatus including means for automatically limiting the return movement of the apparatus from digging to hauling position without the attention of the operator, said hydraulic control unit including pipes having by-pass adjustment cocks arranged to automatically return the scraper to any one of several desired angles without attention of the tractor operator, and cords connecting with operating 120 125 130 135 140 145 150 155 160 165 170 175 180 185 190 195 200

levers whereby the tractor driver can control the apparatus from a distance and secure an infinite number of digging positions by operating the cords.

13. In an apparatus of the character described, the combination with a scraper body, of a post arranged adjacent the rear of said scraper, a draft device connected with said post and with the forward portion of the scraper for tilting the scraper, a hydraulic apparatus mounted on the draft device and operatively connected with the post, and means to control the hydraulic apparatus to regulate the operative digging angle of the scraper.

14. In an apparatus of the character described, the combination with a scraper body, of a draft device connected with the scraper body adjacent the rear thereof, means connecting the draft device with the forward portion of the scraper, hydraulic apparatus mounted on the draft device and operatively connected to the scraper body, and means to control the hydraulic apparatus for regulating the operative digging angle of the scraper.

15. In an apparatus of the character described, the combination with a scraper body, of a draft device connected with the scraper body adjacent the rear thereof, means connecting the draft device with the forward portion of the scraper body, hydraulic apparatus arranged to allow relative movement between the draft device and scraper body, and means to control the hydraulic apparatus for regulating the operative digging angle of the scraper.

16. In an apparatus of the character described, the combination with a scraper body, of a draft device operatively connected to said scraper body at points spaced longitudinally of the draft device, one of the connections between the scraper body and draft device permitting movement of the scraper body relative to the draft device, and hydraulic apparatus arranged to adjustably limit said relative movement.

17. In an apparatus of the character described, the combination with a scraper body, of a draft device operatively connected to said scraper body, said connection permitting limited sliding movement of the scraper body relative to the draft device, and a hydraulic apparatus associated with said sliding connection to regulate and limit the movement of the scraper body relative to said draft device.

18. In an apparatus of the character described, the combination with a scraper body, of a draft device operatively connected therewith, said draft connection permitting relative movement between the draft device and the scraper body, and a hydraulic apparatus associated with said draft connection to auto-

matically limit relative movement between the scraper body and draft device.

19. In an apparatus of the character described, the combination with a scraper body, of a draft device operatively connected therewith, said draft connection permitting relative movement between the scraper body and draft device, and a hydraulic apparatus associated with said draft connection to regulate and limit relative movement between the scraper body and draft device, said hydraulic apparatus comprising a hydraulic cylinder, a piston arranged therein, conduits connected with opposite ends of said cylinder, a control valve operatively associated with said conduits to permit movement of the piston in said cylinder, and means to permit limited movement of the piston in the cylinder independently of the control valve.

20. In an apparatus of the character described, the combination with a scraper body of a draft device operatively connected therewith, said draft connection permitting relative movement between the scraper body and draft device, and a hydraulic apparatus associated with said draft connection to regulate and limit relative movement between the scraper body and draft device, said hydraulic apparatus comprising a piston and a hydraulic cylinder therefor, said piston and cylinder being connected to said scraper body and draft device, conduits connected with opposite ends of the hydraulic cylinder, a control valve operatively associated with said conduits to permit movement of the piston in said cylinder, and a plurality of spaced relief valves associated with said cylinder to permit limited movement of the piston in the cylinder independently of the control valve.

21. In an apparatus of the class described, the combination with a scraper body, of a post connected to said scraper body adjacent the rear thereof and extending thereabove, a draft device having a sliding connection with said post, a bracket on said draft device, a hydraulic cylinder secured to said bracket, a piston arranged in said cylinder and pivotally connected to said post, and fluid conduits connected with said cylinder.

22. In an apparatus of the character described, the combination with a scraper body, of a post extending thereabove adjacent the rear thereof, a draft device slidably connected with said post at a point spaced from its top, a hydraulic apparatus connecting the draft device with the post at a point spaced above the slidable connection for limiting sliding movement between the draft device and the scraper body, and a releasable connection between the front of the scraper body and the draft device.

23. In an apparatus of the character described, the combination with a scraper member, of a draft member having a sliding connection with the scraper member, a hy-

draulic cylinder connected to one of said members, a piston arranged in said cylinder and connected to the other of said members, and means to limit the movement of the piston in the cylinder to limit relative movement between the scraper and draft device.

24. In an apparatus of the character described, the combination with a scraper body, of a draft device operatively connected to the 10 scraper body adjacent the forward end thereof, and hydraulic apparatus connecting the draft device with the rearward portion of the scraper body and arranged to allow relative movement between the scraper body and draft device.

25. In an apparatus of the character described, the combination with a scraper body, of a draft device operatively associated with the front portion of the scraper body, an 20 upstanding member secured to the scraper body adjacent the rear thereof, and a hydraulic apparatus connecting the upstanding member with the draft device and adapted to allow relative movement between the draft 25 device and scraper body.

26. In an apparatus of the character described, the combination with a scraper box, of a draft device operatively connected with the forward portion of the scraper box, and 30 a hydraulic apparatus operatively connecting the draft device with the scraper box and arranged to allow relative movement between the scraper box and draft device during the digging, hauling and dumping operations of the 35 scraper box.

27. In an apparatus of the character described, the combination with a scraper box, of a draft device pivotally connected to the forward portion thereof, and a hydraulic 40 apparatus operatively connecting the draft device with the scraper box and arranged to allow relative movement between the scraper box and draft device during the digging, hauling and dumping operations of the 45 scraper box.

28. In an apparatus of the character described, the combination with a scraper body, of a draft device pivotally connected to the forward portion of the scraper body, a hydraulic 50 cylinder pivotally connected to the draft device, and a piston arranged in said cylinder and pivotally connected adjacent the rear of said scraper body to allow relative movement between the scraper body and draft device.

McLENNEN C. SLATE.
